UNITED STATES PATENT OFFICE.

FRANK P. MILLER, OF MEADVILLE, PENNSYLVANIA.

ROTARY CUTTER.

Application filed May 11, 1926. Serial No. 108,294.

This invention relates to rotary cutters of the inserted blade type and has for an important object the provision of means whereby the blades may be securely locked in place to resist the tendency of the same to move with respect to the carrier when in use.

More specifically, an important object of the invention is to provide an inserted blade rotary cutter in which the blades may be positively locked against endwise and edgewise shifting and in which wear may be easily compensated for.

Other objects and advantages will be apparent during the course of the following description.

In the accompanying drawings forming a part of this application and in which like numerals are employed to designate like parts throughout the same,

20 Figure 1 is a fragmentary perspective of an inserted blade rotary cutter constructed in accordance with this invention;

Figure 2 is a fragmentary sectional view taken on line 2—2 of Figure 1;

25 Figure 3 is a sectional view taken on line 3—3 of Figure 2;

Figure 4 is a fragmentary perspective of a slight modification of the invention;

30 Figure 5 is a detail longitudinal sectional view through the inserted blade rotary cutter, one of the blades being shown in elevation;

Figure 6 is a fragmentary transverse sectional view through the rotary cutter illustrated in Figure 4;

Figure 7 is a group perspective illustrating one of the blades and associated parts by means of which the blade is supported and held in place.

40 In the drawings, the numeral 5 designates a carrier having longitudinal grooves for the reception of blades 6. By reference to Figure 2 it will be seen that each groove is more or less uniformly decreased in width toward the periphery of the carrier and that the blade received therein is also decreased in width toward the outer edge thereof so that when the blade is forced outwardly by a means to be described it will have wedging contact

45 with the walls of the groove and will, therefore, be held firmly in place. In other words, each blade is wedge-shaped in cross-section and is adapted for wedging engagement with the walls of the groove whereby the outward

50 movement of the blade is effectively limited.

In carrying out the invention, a tapered key 7 is positioned between the inner edge of each blade and the bottom wall of the groove and when advanced, as shown in Figure 3, will force the blade 6 outwardly into wedging contact with the walls of the groove, as previously stated. Thus when the blade has been firmly locked in place by the tapered key 7 edgewise movement of the blade is positively prevented as a result of the strain to which the cutter is subjected in use.

The longitudinal thrust on each blade is taken by a locking screw 8, the rear portion of which has threaded engagement with an angularly extended opening in the carrier. The rear portion of the locking screw 8 may be provided with suitable tool engaging means accessible without disturbing any other parts of the carrier. The forward portion of the locking screw 8 is selectively received in notches 9 in the blade 6 and has firm engagement with the wall of one of the notches to hold the blade against endwise movement. Figure 2 clearly illustrates that the forward terminal of the pin 8 is tapered to a point and is adapted for binding engagement with the adjacent portion of the tapered key 7 to hold the tapered key against endwise movement when the same has been adjusted. Of course, the tapered key 7 is adjusted previous to the engagement of the screw 8 with the same. Hence it will be seen that the locking screw 8 not only takes the longitudinal thrust on the blade 6, but also has binding engagement with the key 7 to hold the same positively.

It is believed to be obvious that the cutting diameter of the cutter may be varied by longitudinal adjustment of the blades 6, in which case the screws 8 are temporarily removed.

In the form of invention shown in Figures 4 to 7, inclusive, the carrier is designated by the numeral 15 and is provided with a plurality of grooves 16 for the reception of blades 17. The blades, of course, have conventional or other cutting edges, this feature forming no part of the present invention.

In carrying out the invention, one side wall of each groove 16 is inclined and the other side wall of the groove is provided with separate faces 18 and 19 arranged in intersecting planes for engagement by the opposed faces of a wedge 20 and a taper pin 21, respectively. Figure 7 plainly illustrates that the wedge 20 is decreased in thickness toward the

outer edge thereof so that when the same is forced outwardly the wedge will have binding engagement on one side with the wall 18 and on the other side with the blade 17 whereby the blade is securely and positively held in place.

It might be said that the taper pin 21 is provided with a beveled outer surface 23 for contact with the face 19 of one side wall of the groove so that when the taper pin is advanced it will force the wedge 20 outwardly. Particular attention is directed to the fact that the pin 21 when advanced not only exerts an outward pressure on the wedge 20, but also has pressure contact with the adjacent side of the blade 17 whereby to cooperate with the wedge in firmly holding the blade in place.

The end thrust on each blade may be taken by a series of pins 26 extended through angularly directed openings 27 in the body of the carrier. The openings 27 intersect the grooves 16 at the bottom wall thereof as shown in Figure 6 so that it is the intermediate portions of the pins 26 which have engagement with the pins 27. The end portions of the pins 26 are firmly anchored in the openings 27 so that the intermediate portions of the pins 26 may offer the maximum resistance to the end thrust on the blades. The pins 26 are selectively extended through diagonal notches 29 in the beveled surfaces 30 of the blades so that the end thrust on the blades is taken by the pins.

In summarizing the form of invention shown in Figures 4 to 7, inclusive, it might be said that the same consists of a carrier having grooves and that one side wall of each groove is substantially V-shaped in cross-section for engagement by separate wedging members which act to firmly hold the blades against edgewise movement and that the blades are positively held against longitudinal movement by means of separate pins employed for that purpose.

While the invention has been shown as especially applied to milling cutters, it is obvious that the inventive idea involved may be carried out in connection with milling cutters, reamers, tool-holders for lathes, counter borers, and the like.

Having thus described the invention, what is claimed is:

1. A rotary cutter comprising a body having a groove, a blade in the groove, a key to hold the blade in place, and a screw carried solely by the body and having intersecting locking engagement with the blade and being in pressure contact with the key to hold the same in place.

2. A rotary cutter comprising a carrier having a groove, a blade in the groove and having a notch, a key engaged with the blade to hold the same in place, and a locking device extending entirely through said notch to hold the blade against shifting and hav-

ing the forward terminal thereof in pressure engagement with said key to hold the key in place.

3. A rotary cutter comprising a carrier having a groove, a blade in the groove, a key having wedging engagement with the inner edge of the blade to force the same outwardly, and a locking screw having secure engagement with said blade and said key to hold both of these parts in adjusted position.

4. A rotary cutter comprising a carrier having grooves decreased in width toward the periphery of the carrier, blades in said grooves and being decreased in width toward the outer edges thereof for binding engagement with the side walls of the grooves, keys engaged with said blades to force the same outwardly, and locking devices engaged with said blades to hold the same against longitudinal movement, the forward portions of said locking devices being tapered and having pressure engagement with said keys to hold the same against longitudinal movement.

5. The construction set forth in claim 4, said blades being provided with notches selectively and snugly receiving portions of said locking devices.

6. A rotary cutter comprising a carrier having grooves gradually decreased in width toward the periphery of the carrier, blades received in said grooves and being decreased in width toward the outer edges thereof and having beveled surfaces provided with notches, and locking screws carried by the body and selectively extended through said grooves and engaging the walls of the same to hold said blades against longitudinal movement.

7. A rotary cutter comprising a carrier having grooves gradually decreased in width toward the periphery of the carrier, blades received in said grooves and being decreased in width toward the outer edges thereof and having notches, locking screws carried solely by the body and selectively extended through said notches to hold said blades against movement, and wedging means to force said blades into pressure contact with the walls of said grooves.

8. A rotary cutter comprising a carrier having grooves decreased in width toward the periphery of the carrier, blades received in said grooves and being decreased in width toward the outer edges thereof and having beveled surfaces provided with notches, locking screws carried by the body and selectively extended through said notches and engaging the walls of the same to hold said blades against movement, wedging means to force said blades into pressure contact with the walls of said grooves, said locking screws having pressure contact with said wedging means to hold the same firmly in place.

9. A rotary cutter comprising a carrier

having grooves, the walls of which converge, blades received in said grooves and having converging side walls adapted for flatly contacting with the walls of the grooves, wedging means to force said blades into binding engagement with the walls of the grooves, and locking screws having threaded engagement with the body and engaged with said blades and having their forward portions tapered 10 and in pressure contact with said wedging means.

10. A rotary cutter comprising a body having a groove, a blade in the groove, a wedging key to secure the blade in place, and a

fastening screw carried by the body and having interlocking engagement with the blade and having the forward terminal thereof in pressure contact with the wedging key to hold the wedging key in place. 15

11. In a rotary cutter, a body having a groove, a pair of members in the groove, and a locking screw carried solely by the body and having interlocking engagement with one of the members and having pressure engagement with the other member to hold both 25 of the members in place.

In testimony whereof I affix my signature.

FRANK P. MILLER.
